UNITED STATES PATENT OFFICE

172,876

CHILD'S TOY CHEST

Robert Goldman and Roy R. Nemzer, South Hempstead, N. Y., assignors to Bo-Low Lamp Corp., Brooklyn, N. Y., a corporation of New York

Application February 8, 1954, Serial No. 28,896

Term of patent 7 years

(Cl. D34—15)

To all whom it may concern:

Be it known that we, Robert Goldman and Roy R. Nemzer, both citizens of the United States and residents of South Hempstead, in the county of Nassau, State of New York, have invented a new, original, and ornamental Design for a Child's Toy Chest, of which the following is a specification, reference being had to the accompanying drawing, forming a part thereof, and of which:

Fig. 1 is a top plan view of a child's toy chest showing our new design.

Fig. 2 is a front elevational view of our design shown in Fig. 1.

Fig. 3 is a right side elevational view thereof.

Fig. 4 is a rear elevational view thereof, and Fig. 5 is a bottom plan view thereof.

We claim:
The ornamental design for a child's toy chest, as shown.
